US00D552225S

(12) **United States Design Patent** (10) **Patent No.:** **US D552,225 S**
Borovicka et al. (45) **Date of Patent:** **** Oct. 2, 2007**

(54) **AIR CLEANER**

(75) Inventors: **Cory Borovicka**, San Francisco, CA (US); **Mark Turner**, Mechanicsville, VA (US)

(73) Assignee: **Hamilton Beach/Proctor-Silex, Inc.**, Glen Allen, VA (US)

(**) Term: **14 Years**

(21) Appl. No.: **29/255,546**

(22) Filed: **Mar. 9, 2006**

(51) **LOC (8) Cl.** **23-04**

(52) **U.S. Cl.** **D23/364**

(58) **Field of Classification Search** D23/364, D23/359, 355, 356, 360, 362, 386, 352, 366, D23/369, 332, 333, 335, 336, 342, 381, 387; 55/356, 473, 504, 471; 210/497.1; 96/97; D14/188, 170, 172, 242; D24/110; 422/120, 422/122

See application file for complete search history.

(57) **CLAIM**

The ornamental design for an air cleaner, as shown and described.

DESCRIPTION

FIG. 1 is a top perspective view of an air cleaner in accordance with my new design;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof; and,

FIG. 7 is a bottom plan view thereof.

The broken lines in the figures are for illustrative purposes only and form no part of the claimed design.
